United States Patent Office

Des. 196,528
Patented Oct. 8, 1963

196,528

KEY BLANK OR SIMILAR ARTICLE

Fred J. Russell, 8635 Otis St., South Gate, Calif.

Filed Feb. 5, 1963, Ser. No. 73,449

Term of patent 14 years

(Cl. D50—4)

FIG. 1

FIG. 2

FIG. 3

FIGURE 1 is a side elevation of a key blank showing my new design.

FIGURE 2 is a side elevational view on the side opposite FIGURE 1.

FIGURE 3 is an end elevational view.

I claim:

The ornamental design for a key blank or similar article, as shown.

References Cited in the file of this patent

Premium Practice Magazine for January 1950, page 146, third key up from bottom of page.

Western Aviation Magazine for April 1960, page 130, illustration at lower right of page.